UNITED STATES PATENT OFFICE.

GEORG HENRY ASCHENBACH, OF WASHINGTON, DISTRICT OF COLUMBIA,
ASSIGNOR OF ONE-HALF TO ALBERT L. JACKSON, OF SAME PLACE.

NIPPLE-HOLDER.

SPECIFICATION forming part of Letters Patent No. 429,832, dated June 10, 1890.

Application filed October 29, 1889. Serial No. 328,523. (No model.)

To all whom it may concern:

Be it known that I, GEORG HENRY ASCHENBACH, a citizen of the United States, residing at Washington, in the District of Columbia, have invented certain new and useful Improvements in Nipple-Holders; and I do hereby declare the following to be a full, clear, and exact description of the invention, such as will enable others skilled in the art to 50 which it appertains to make and use the same.

My invention relates to certain new and useful improvements in nipple-holders.

The object of the invention is to obtain a device of the character described which will 55 form a positive and certain guide for the nipple when inserted into the stock of the screw-threading machine, which will enable it to be used with nipples of various sizes, and the construction of which will be such as to render the removal of the nipple from its holder convenient.

To the accomplishment of the above the invention consists in certain novel parts and combination of parts, as will be hereinafter 60 fully described and specifically claimed, reference being had to the accompanying drawings, in which—

Figure 1 is a longitudinal section of the holder and the shank used in connection 65 therewith; Fig. 2, a view in perspective of the holder detached from its shank, and Fig. 3 a similar view of the shank in modified form.

In the drawings, A represents a holder, 70 which consists of a piece provided with a screw-threaded bore and of such a size as to fit snugly within the stock of a screw-threading machine. At its forward end the bore of this holder or guide is made to correspond to 75 the size of the particular nipple with which it is to be used, it being my intention to manufacture and supply the trade with a set of such holders or guides, one for each of the standard-sized nipples. The bore at the rear 80 end of this holder or guide is adapted to fit the end of the shank B in connection with which it is to be used, and, as this bore to accommodate such shank must always be larger than the bore for the nipple, a shoulder 85 a is formed within the holder or guide, against which the end of the shank impinges

when the parts are in position for use, as shown in Fig. 1.

The shank B is screw-threaded at one end and adapted to be secured into the rear end of 55 the guide or holder A a sufficient distance to impinge against the shoulder of the guide, as above described, and to form a shoulder against which the inner end of the nipple impinges when it is in a position to be operated 60 upon by the screw-threading device.

The shank shown in Fig. 1 is adapted for use in connection with holders arranged to accommodate the three smaller sizes of the standard-sized nipples, and for the three 65 larger sizes of such nipples a larger-sized shank may be used, or, preferably, the shank should be constructed as shown in Fig. 3, wherein it is shown as screw-threaded upon both ends, the different ends of such shank 70 being of different sizes. In this way a set of tools constructed on my plan would consist of six holders or guides and a single shank, one end of such shank being designed for use in connection with three of such holders and 75 the opposite end in connection with the remaining three.

Upon the outer face of the holder or guide A, and at the rear end thereof, I provide a 80 holding-surface D, which may be made in any suitable manner, such as the square-shaped or four-sided projection shown in the drawings, by means of which the ready detachment of the guide or holder from its shank is provided for.

By the use of a device of the character named, constructed as herein described, it will be seen that a nipple-holder which will be simple in construction, and which will form a positive guide for the nipple when inserted in the stock of a screw-threading machine, is obtained, and, further, by having the holder or guide detachable from its shank the nipple may be more readily removed from 90 its holder.

Having thus fully described my invention, what I claim as new therein, and that for which I desire to secure Letters Patent, is—

1. The combination, with a nipple-holder provided at one end with a screw-threaded 100 bore to receive the nipple and at the opposite end with a screw-threaded bore for the

shank, of a screw-threaded shank, the holder serving as a guide in the stock, and the shank and holder detachably connected, as set forth.

2. The combination, with a nipple-holder

5 provided at one end with a screw-threaded bore for the nipple and at the opposite end with a screw-threaded bore for a shank, and also provided with a holding-surface, of a screw-threaded shank, the holder serving as

10 a guide in the stock, and the shank and holder detachably connected, as set forth.

3. The combination, with a nipple-holder provided with a screw-threaded bore for the nipple and a screw-threaded bore for a shank

15 and a shoulder formed on the inner end of

the shank-bore, of a screw-threaded shank, the holder serving as a guide in the stock and the shank as a shoulder for the nipple, as set forth.

4. As a new article of manufacture, a shank 20 for nipple-holders, provided with screw-threaded ends of different circumferences, as set forth.

In testimony whereof I affix my signature in presence of two witnesses.

GEORG HENRY ASCIENBACH.
